UNITED STATES PATENT OFFICE.

LEON A. ROBINSON, OF PEORIA, ILLINOIS.

ATTACHMENT FOR LINE-CASTING MACHINES.

Application filed November 7, 1921. Serial No. 513,339.

To all whom it may concern:

Be it known that I, LEON A. ROBINSON, a citizen of the United States, residing at Peoria, in the county of Peoria and State 5 of Illinois, have invented new and useful Improvements in Attachments for Line-Casting Machines; and I do hereby declare that the following is a full, clear, and exact description of the invention, which will enable others skilled in the art to which it 10 appertains to make and use the same.

This invention relates to a machine for casting a slug from a line of assembled matrices and spaces.

15 Said invention pertains more particularly, however, to an attachment for a machine of the type named for positively preventing the action of the pump which operates to force the type metal to the matrices to cast 20 a line, whenever conditions are not favorable for making such cast.

The main object of my invention is to provide a mechanism in a line casting machine for preventing the action of the pump 25 when the mold and matrices are not in proper register.

Another object is that of providing mechanism for attachment to a machine of the present day type by which the operation of 30 the pump may be positively controlled and prevented acting except under favorable conditions for casting a perfect slug from a line of full length.

Still another object is to provide mechanism which, while preventing the operation of the pump, as is now done when a short line is sent into the machine, will also prevent action of said pump whenever the mold and the matrices fail to properly register or 40 whenever there is an imperfect contact between said matrices and said mold even though the line may be of the proper width.

A further object is to include mechanism in a machine of the type named, interposed 45 between the pump actuating mechanism and a part of the machine operable automatically and only at the time the mold and matrices have proper positions relatively for casting a perfect line or slug.

50 A still further object is to combine with any usual pump-releasing mechanism means including a part disposed in position to be actuated by a portion of the machine at the time a line is to be cast for releasing

said pump but which can only be operated 55 for such release when ideal conditions for casting a line exist.

Again, an object is to furnish mechanism which during the operation of the machine will be automatically operated to move the 60 right-hand jaw to close the line in connection with and prior to the casting operation, followed by the reaction of the jaw during "justification" to operate said mechanism for releasing the pump. 65

A still further object is to furnish an attachment for a line casting machine that while operating to release the metal-pump will act at the same time to place pressure 70 upon the movable jaw of the machine to assist in the casting of a perfect slug or line.

Besides these objects the invention relates to certain details of construction and arrangement of parts which will form the subject of some of the claims herein. 75

To the end that my invention may be fully understood I have provided the accompanying drawings where:

Figure 1 is a side elevation on a reduced scale of parts entering into the construction 80 of one of the common types of line casting machines showing my invention attached thereto.

Figure 2 is a plan of the same.

Figures 3, 4, 5 are respectively a rear 85 elevation, a vertical transverse section, and a plan of one of the operating mechanisms included in my invention.

Figure 6 shows the body of the said mechanism in perspective. 90

Figures 7 and 8 are sectional elevations of portions of the line casting machine, parts shown in Figures 1 and 2 being produced substantially their full size showing two different positions thereof, or true line casting position and faulty position respectively of the mold and matrices. 95

Figure 9 illustrates in perspective parts of the machine shown in Figures 1 and 2 with my invention in connection therewith; 100 and

Figure 10 is an elevation of certain parts of the machine showing in connection therewith the mechanism illustrated in Figure 4, but viewed from the side opposite that 105 shown in said figure.

In machines of the present day construction a "pump stop" is employed, as is well

- known, to prevent the casting of a line when such line is too short; that is to say, when the matrices and "spaces" do not constitute a full line. But the means employed does 5 not prevent the operation of the pump when the mold and matrices are not in proper register, i. e., when the toes of the matrices are not seated snugly into the groove or grooves of the mold.
- 10 Quite often, for one reason or another, the so-called "first elevator", after the line of matrices and spaces has been sent into it, does not descend its full distance or to the proper casting position. The result is that 15 the toes of the matrices do not lie opposite the groove or grooves in the mold and in the succeeding closing-up movement of the mold they cannot enter such groove or grooves, the mold being held away from 20 the matrices thereby, leaving a space through which the metal may be forced, resulting in a "squirt", the metal being thrown over and through the working parts of the machine and between the matrices 25 and much time is lost in cleaning the machine.

The operator cannot be apprised of these 30 impending difficulties except by either keeping a practiced eye upon the elevator to see that it is in proper position, or by constantly attempting to discern by unfamiliar sounds the improper action of the parts which, of course, takes his attention more or less, from his key-board.

35 One of the purposes of my invention in view of the above, is to provide and so place the release mechanism for the pump that instead of being operated in sequence with the movement of the mold toward the matrices, it will be operated to release the pump when and as the fitting or nesting or seating of the mold and matrices become perfect, thus eliminating entirely the described 40 difficulties.

45 In the figures, 1 and 2 represent parts of certain frame-portions of a line casting machine, and 3 is the so-called "first elevator" usually guided by and movable with respect to the said portion 2, and having 50 the usual elevator jaws 3.

The usual mold is designated at 4, while 5 is the mold-wheel.

Rearward of the mold-wheel is the pivotally mounted metal-pot 6 adapted to be tilted 55 toward the mold-wheel as in common practice, combined with which is the customary plunger or pump 7 with which is connected a lever 8 pivoted on an arm 9, for example, of the frame-portion 1, operated both by a cam 10 and a spring 11, while 12 is the cam for carrying the metal-pot 6 toward the mold-wheel 5.

60 Thus far described, the machine conforms substantially to those now in use, no claim 65 being made thereto per se, though other

parts thereof will be referred to herein in order to better explain the disposal of those parts included in my invention and their operations in connection therewith.

A bracket 13 secured to the frame portion 70 1 carries an arm 14 upon which is pivoted at 15 a bell-crank lever 16, one arm of which is designed to lie beneath a depending extension 17 and the lever 8 previously referred to, all of which is likewise in common use, 75 said lever 16 holding said lever 8 raised and normally preventing the spring 11 from depressing it for the operation of the plunger 7, a spring 18 being provided to elastically hold the lever 16 in its position beneath 80 said extension 17. Pivoted on said arm 14 at 19 is a lever 20, to engage the other arm of the lever 16, and pivoted to part of said lever 20 is a two-piece rod 21 guided in an arm 22 on a stud 23, for example, of the 85 arm 14, a thumbscrew 24 being employed to secure said arm 22 in any desired adjustment, such adjustment being merely for the purpose of properly positioning the rod 21 with respect to other parts to be described, 90 but any other securing means may be used in place of that described.

A turn-buckle 25 or other desired means is carried by the two parts of the rod 21 by which to adjust such parts relatively for a greater or less length, said rod extending in the direction of the right-hand vise-jaw 26; see particularly Figures 9 and 10. The other vise-jaw is indicated at 26' in Figure 2.

The said jaw 26 is customarily mounted 100 slidably upon the frame portion 2, the mounting therefore being unnecessary to describe, since well known. It has a recess 27 in that side thereof lying adjacent the said frame portion 2, partially within which lies 105 a support 28. As shown in Figure 6 this support is of U form, by preference, the yoke portion thereof being secured to the said frame portion 2 by screws 29, for example, the extensions projecting toward said 110 jaw. Pivoted at its lower end between the extensions near the lower end of said support is what may be termed a finger 30, there being a bail 31 freely suspended from the support, there also being a pin 32 extending through the latter which may carry 115 both the bail and the finger pivotally, as shown.

One end of a spring 33 is secured to the bail and the other end thereof extends upwardly between the support and said finger 30 adapted at times to bear against the latter.

120 Mounted pivotally upon the top of one of the extensions of the support is an L-shaped trigger 34, one of the arms 34' of which lies partially across the recess between the said extensions adapted at times to have contact with the finger 30. The other arm 34' of the trigger, as shown in Figures 9 125 130

and 10, lies behind a part 26² of the jaw 26, a screw 35 therein adapted to engage the same and in turn to be engaged by said jaw. The same is adjustable within the arm 5 and is secured by a lock-nut 36.

A spring 37, preferably stronger than the spring 33, is secured at one end to the bail 31. It extends upwardly at its other end and terminates behind the trigger as 10 most clearly shown in Figure 10. Attached to the bail is a pin 38 upon which is threaded a sleeve 39 secured by a lock-nut 40, said sleeve extending through a hole 40' in the jaw 26 in the direction of and adapted, under certain conditions, to receive contact 15 of a portion of the mold-wheel 5, Figures 9 and 10, the finger 30 adapted also, under certain conditions, to operate the rod 21 as will appear presently.

20 In Figure 7 one of a series of matrices 41 is shown in position between the grooved mold and the correspondingly grooved elevator jaw in ideal casting position, the mold-wheel, metal-pot and the elevator 3 carrying 25 the matrices; lying in proper position for casting a line.

In Figure 8, however, the elevator has not descended to the normal line casting position which may be due to one of several causes 30 not necessary to mention, and, in consequence, the toes 42 of the matrices cannot enter the groove 43 of the mold. Now, since a gap is thus left between the matrices and the mold equal in width to the length of 35 the toe 42, the metal if flowing would be free to squirt from said gap since unconfined.

In order to fully understand my invention 40 and its advantages it is to be remembered that the pump releasing mechanism is not to be released by the machine in the usual operation following the sending in of a line and the casting thereof, but must be released only when and as the mold has moved up 45 to its exact seating position as explained. That is to say, referring to Figures 9 and 10, it is seen that the pump-release mechanism extends between the usual lever 16, or 50 its equivalent, and the finger 30 of the support 28, the rod 21 normally having but slight contact with said finger. Also, it is to be observed, that the sleeve 39 of the bail 31 lies in position to be engaged by the mold-wheel.

55 Now, the elevator 3 having descended to its proper or normal position, Figure 7, so that the mold and matrices can properly register the mold-wheel in its subsequent movement to carry said mold metal-tight upon the matrices will strike the said sleeve 39. But this cannot occur if the toes of the matrices prevent the full movement of the parts, see Figure 8.

The normal position of the trigger 34 is substantially as shown in Figure 5, the screw 35

of its arm 34² lying against the part 26² of the jaw 26 as in Figure 9. The mold-wheel in advancing to its limit, and having now moved the sleeve by the pressure thereon, causes the jaw to be moved to close up the matrices by 70 forcing the spring 37 against the trigger to carry the said screw 35 against said jaw, the arm 34² of said trigger preventing the finger 30 having pressure upon the rod 21. Subsequently, the jaw is shifted backward in opposition to the trigger during "justification", whereupon the finger 30 is released by the said arm 34². The spring 33, which has been under tension against the said finger, due to the movement of the bail 31 and its sleeve now causes said finger to exert pressure upon the rod 21 and shifts it to remove the lever 16 from beneath the arm 8 permitting the spring 11 to operate the pump. 75 80 85

A perfect line or slug is now cast, since the nesting of the matrices and mold is perfect. In a succeeding operation if this proper nesting or seating does not take place and these parts cannot come together, the mold-wheel cannot advance far enough to reach and 90 move the sleeve 39 and therefore there can be no flow of metal under such circumstances.

The construction of the device of my invention may be varied, of course, without departing from the spirit and intent of the invention and I do not confine myself to employing the movement of the mold-wheel, and its pressure upon the sleeve 39 since pressure of some member other than the said 95 mold-wheel may perform the same service. 100

Preferably the said sleeve 39 and the screw 35 of the arm 34², are adjustable in order to permit them to conform to conditions that may exist in any given machine, which is likewise true of the two part rod 21. While the device can be made to release the pump after the mold and matrices properly seat in perfect line casting position, it is preferable, of course, through the action of 110 the jaw 26, that the release occur only after the line of matrices has been expanded to its proper width.

Said jaw is free to move as the line of matrices and spaces is sent in between it and the fixed jaw, there being no restraint placed upon it at such times as is commonly the case. Disastrous results often attend the act of forcing a full line between the jaws when one of them is elastically controlled. My structure provides for an entirely free, movable jaw or one having no restraint placed upon it during the time of entrance of the line, elastic pressure being applied to said jaw by the means described only when the line has taken a fixed position between the two jaws. 115 120 125

Having described the invention, I claim:

1. A line casting machine including in combination with its mold-wheel and a 130

freely movable vise-jaw, a part engaged and moved by the mold wheel, and a second part operated by the first said part adapted to elastically engage and operate said jaw for closing it elastically upon a line of matrices.

2. A line casting machine including in combination with its mold-wheel and a freely movable jaw, a support secured on the frame of the machine, a part mounted on the support adapted for pivotal movement and to be engaged and moved by the said mold wheel, a second part pivoted on the support adapted to engage the jaw, and elastic means interposed between the parts operated by the first named part through which to transmit movement to the said second part.

3. A line casting machine including in combination with its mold wheel adapted for lateral movement, and a freely movable vise jaw, a pivotally mounted part engaged and moved by said mold wheel in its lateral movement, a second part pivotally mounted adapted to engage and move the vise-jaw toward a line of matrices behind the same, and means secured to one of the parts adapted to engage flexibly the other part whereby a yielding pressure is imposed upon said vise-jaw through said parts from said mold-wheel.

4. A line casting machine including in combination with its mold wheel adapted for movement laterally, a freely movable vise-jaw, and pump releasing mechanism, a part pivotally mounted adapted to receive pressure of the mold wheel in the lateral movement thereof, a second part pivotally mounted adapted to engage the vise-jaw, means interposed between the two parts for imparting pressure elastically from one to the other, a third part also pivotally mounted, elastic means operated by the first named part for moving the third part, and an operating mechanism interposed between said third part and said pump releasing mechanism.

5. In a line casting machine including a pump and pump releasing means, a normally freely movable vise-jaw, and a machine part having a given movement when a line is to be cast, in combination with mechanism interposed between the jaw and said part including a lever and means to move the same elastically in the direction of the jaw, a finger, elastic means on said mechanism adapted to bear upon the finger, and operating means interposed between the finger and the pump releasing means, the parts being arranged whereby pressure of the machine part upon said mechanism will move the lever elastically against the jaw and in the path of the finger and elastically hold the latter against the lever.

6. In a line casting machine, the combina-

tion with a pump releasing means, a vise-jaw and a machine part adapted to have a given movement when a line is to be cast, of mechanism mounted on the machine operated by the said machine part to move it against the said jaw for closing up a line from which a cast is to be made, means to operate the pump releasing means, and a finger operated by said mechanism to operate said means, the several parts being arranged and adapted to coact whereby in a single movement of said machine part said jaw is operated followed by the operation of said finger to release the pump.

7. The combination with the pump releasing means and the mold-wheel of a machine of the class described, of mechanism at one end engaging said means and at its other end lying in the path of movement of said mold-wheel, adapted to be operated to release the pump when and as the said mold-wheel completes its full movement in the seating of the mold upon the matrices.

8. The combination with the pump releasing means, and the mold-wheel in a machine of the class described, of mechanism to engage and operate said means engaged by the said mold-wheel when and as the latter completes its full movement to line casting position, to release the pump.

9. The combination with the pump releasing means, and the mold-wheel in a machine of the class described, of a lever mechanism mounted in the path of the mold-wheel engaged thereby in its movement, and mechanism lying between the said lever mechanism and said means operatively engaging the said means and in position to be engaged by the said lever mechanism.

10. The combination with the pump releasing means and the mold-wheel in a machine of the class described, of a lever mechanism mounted on the machine adapted to be engaged by the mold-wheel when and as it completes its full movement to the line casting position, and mechanism interposed between the said means and the said lever mechanism adapted to be engaged and operated by the latter to operate said means and release the pump.

11. The combination with the pump releasing means, the mold-wheel, and a movable vise-jaw in a machine of the class described, of a lever mechanism mounted on the machine including a part to engage the said jaw and a part engaged by the mold-wheel to apply pressure to the first said part to shift the said jaw, a third part, and mechanism mounted between the said releasing means and said third part adapted to be operated by the latter to effect the release of the pump.

12. The combination with the pump releasing means, mold-wheel and a shiftable vise-jaw in a machine of the class described,

of a mechanism mounted on the machine including a part adapted to be engaged by the mold-wheel when and as that member moves to its proper seating position for casting a line, a lever operated by said part to engage and shift the said jaw, a third member controlled by the lever and released thereby in the return movement of the jaw, and mechanism lying between the said third part and the said releasing means operated by the former to move the latter for releasing the pump.

13. The combination with the pump releasing means, mold-wheel, and a movable vise-jaw of a machine of the class described, of mechanism in position to operatively engage the said means to release the pump, a part to receive pressure of and to be held in an extreme position by the mold-wheel as the latter reaches its extreme position for casting a line, a lever to engage the said jaw, a part operated by the first said part to apply elastic pressure to the lever to move the said jaw therethrough, a finger in position to engage the said mechanism but held from such engagement by said lever, and an elastic member operated by the said first named part to operate said finger to engage and operate the mechanism to release the pump when and as the said jaw in its re-

turn movement removes the lever from contact with said finger.

14. Mechanism for use in the operation of a pump releasing means in a machine of the class described, including in its construction 35 a support, a bail pivoted thereto, a trigger pivoted on said support, a part secured to the member to elastically engage the trigger, a finger pivoted on the support in position to be engaged by the trigger, and an elastic member secured on the said member and positioned to engage the finger.

15. Mechanism for use in the operation of a pump releasing means in a machine of the class described, including in its construction 45 a support, a bail pivoted thereto, a trigger pivoted on said support, a part secured to the member to elastically engage the trigger, a finger pivoted on the support in position to be engaged by the trigger, a member 50 secured on the said member and positioned to elastically engage the finger, and an operating part interposed between said finger and said releasing means.

In testimony whereof I affix my signature 55 in presence of two witnesses.

LEON A. ROBINSON.
